UNITED STATES PATENT OFFICE.

ERNEST H. VOWLES, OF FITCHBURG, MASSACHUSETTS, ASSIGNOR TO FITCHBURG BOBBIN CLEANING MACHINE COMPANY, A CORPORATION OF MASSACHUSETTS.

BOBBIN-CLEANING MACHINE.

Application filed September 1, 1921. Serial No. 497,583.

To all whom it may concern:

Be it known that I, ERNEST H. VOWLES, a citizen of the United States, residing at Fitchburg, in the county of Worcester and 5 State of Massachusetts, have invented a new and useful Bobbin-Cleaning Machine, of which the following is a specification.

This invention relates to a machine for cleaning the waste from bobbins. The principal objects of the invention are to locate bobbins in proper position for cleaning and to clean them automatically and continuously; to provide a construction of the rotary type for the purpose of securing 15 continuous operation wherein the feeding and slipping of the bobbins will be in different stages of progress on several bobbins at the same time; to provide improved means for supporting the bobbins, guiding 20 them in their course, forcing them to move through the stripping jaws and ejecting them from the machine when cleaned, and ejecting the filling also; to provide improvements in the jaws for performing the cleaning operation and in the means for operating 25 said jaws; and to provide improved mechanism for operating the respective parts of the machine.

Further objects and advantages of the invention will appear hereinafter.

Reference is to be had to the accompanying drawings in which

Fig. 1 is a plan of machine constructed in accordance with this invention;

Fig. 2 is a central sectional view on the line 2—2 of Fig. 1 showing the base and some other parts in side elevation;

Fig. 3 is a sectional view of one of the hoppers on the curved line 3—3 of Fig. 1;

Fig. 4 is a sectional view of one of the hoppers on the radial line 4—4 of Fig. 1;

Fig. 5 is a plan on an enlarged scale of the mechanism for opening and closing the jaws, showing certain parts in section on the line 5—5 of Fig. 2;

Fig. 6 is a sectional view of a pair of jaws in closed operative condition on the line 6—6 of Fig. 5;

Fig. 7 is an enlarged sectional view on a vertical plane through the center of one of the bobbin conveying tubes showing parts in elevation;

Fig. 8 is a sectional view on the line 8—8 of Fig. 2;

Fig. 9 is a plan of the stripping jaws;

Fig. 10 is a sectional view of one of the yielding means for operating the jaws on the line 10—10 of Fig. 5;

Fig. 11 is a view of the surface of the cylindrical cam laid out flat, and 60

Fig. 12 is a bottom plan view of the cam cylinder showing the cam grooves thereon.

The invention is intended for use with an automatic feeding device or it can be fed by hand. It is shown as provided with a base 65 10 having an upwardly extending arm 11 constituting a part of the frame. The top of said arm projects over to the center of the machine radially and supports the top of a vertical shaft 12 extending up from 70 the base. This shaft is pinned to the base and arm 11 to prevent its rotation.

Supported by the base, and preferably also by the arm 11, is a driving shaft 13 receiving power from tight and loose pulleys 75 14 or in any other desired way. Through bevel gears 15 it transmits power to a vertical shaft 16 supported on the base. At the top of this shaft 16 is a pinion or gear 17 meshing with a spur gear 18 which is fixed 80 to a rotary disc 19. This disc 19 has a hub journaled to rotate on the stationary shaft 12.

When the driving shaft is rotated continually the disc rotates in the direction of 85 the arrow in Fig. 1. Near its circumference this rotary disc 19 carries a plurality of projections to which are bolted carriers 20 having thereon supports 21 for a plurality of bobbin guides 22, in the form of tubes. 90 I have shown six of these as surrounding the circular disc 19 but any desired number can be employed.

Each one of the tubular guides is fitted at the top into the bottom of a hopper 23. 95 These hoppers are arranged so that they constitute a complete circle at the top as indicated in Fig. 1. Each one has a central outlet opening 24 at the bottom, its walls slanting down to this opening. Bobbins introduced into the circle of these hoppers will necessarily each fall into one of them and eventually assume an upright position and slide down, butt end first, through the outlet or opening 24 into the concentric 100 tube 22 below. The bobbins can be introduced, as stated, by hand or by a feeding mechanism that will arrange them with their butt ends down. These hoppers rotate of course with the disc 19. The framework 105 110

is provided with a spider consisting of radial arms 25 at the top extending from a hub freely rotatable on the stationary shaft 12. This with the carriers 20 constitutes a frame for supporting the hoppers and tubes and certain other features as will appear.

Underneath the series of tubes 22 at the bottom is a stationary stop 27 of arcuate form adapted to hold the bobbins throughout a part of a revolution and then allow them to drop down through the bottoms of the respective tubes in which they are located. The tubes are also provided with openings 28 through their sides through which project pivoted stops 29, each adapted to move inwardly and hold a bobbin in elevated position in the tube until the ends of the stops 29 engage an arcuate cam 30 on the stationary arm 11 to open the stop or, in other words, swing it outside the tube where it will have no effect. A spring 26 tends to close each stop in opposition to the cam.

Each carrier 20 extends up at the sides at 31. Between these spaced sides 31 at the top is located the bottom of an upright guiding member 32 which is bolted to the spider 25 at the top. Thus these guides rotate with the disc 19 and spider 25. Brackets 9 at the circumference carry the hoppers 23.

Each guide 32 carries a vertical slide 33. Each of these slides has a cam roller 34 operated in a manner to be described projecting radially inward and mounted on a radial stud. It is also provided with a vertical rod 33^a oscillatably mounted thereon and having a pusher head 35 on the bottom. The pusher head has a conical lower surface for engaging the end of a bobbin and pushing it down through the tubular guide 22. This pusher head extends into the tube 22 through an opening in the side and is adapted to move down in the tube, then to swing outwardly through this opening in its side and enter it again further along. The swinging motion is controlled by an arcuate stationary cam 36 which is engaged by an arm 37 on the top of the rod 33^a as the frame rotates. The rod 33^a is provided with a spring 38 for yieldingly holding the head 35 down and exerting a yielding downward pressure so that it will give in case it meets with any undue resistance.

Each guide 32 is also provided with a vertical slide 40 having an inwardly extending cam roller 41 for operating it and provided at the bottom with a radial plate 42 having two horizontal studs 43 each provided with a jaw. Each stud also has an arm 45 extending from it. These two arms normally project downwardly and are connected by a spring 46 for holding the arms inward toward each other and the jaws normally in yielding contact with a couple of stops 47.

As will appear later these jaws receive the bobbin B.

Fixedly mounted on the stationary shaft 12 by means of a bottom plate 18 and an upper spider 49 is a cylinder 50. This cylinder has a cam groove 51 for the roller 34 and a cam groove 52 for the roller 41. Both of these grooves extend all the way around the cylinder as indicated in Fig. 11. From the shape of these grooves as shown in that figure it will be seen that each upper roller 34 is held at the top for a part of a revolution and then descends rather suddenly to its lowest position at 51^a and then gradually rises to its uppermost position. This gradually results in the lowering of the pusher head 35 and then raising it again. The groove 52 has a substantially horizontal portion at the top of its travel which, at a point 52^a near the point 51^a, commences to descend. In other words, when the roller 34 commences to move up, the roller 41, which has been for awhile in its highest position, immediately commences to descend. Therefore, as soon as the pusher 35 commences to rise the studs 43 commence to go down and they descend until the point 52^b of the cam groove 52 is reached and then rise quickly.

On the bottom of the cylinder 50 there are also two cam grooves 53 and 54, one inside the other. In the groove 53 travel a series of rollers 55 equal in number to the number of bobbin chutes and in the groove 54 travel a corresponding number of rollers 56. Each of these rollers accomplishes a similar result. Each one is mounted on a stud on an arm 58 which is pivoted on a stud 59 on the rotating disc 20. These studs travel around with the plate and the two sets of arms 58 oscillate upon them as they move. Each one is provided with a socket so that these parts constitute a lever. Into the sockets of one series extend rods 60 each of which is provided with a longitudinal slot centrally extending through it for receiving at its two ends a pair of flanged plates 61. Between these plates is a spring 62 pressing them apart. Opposite each of the studs 59 is another stud 63 which has a 115 socket head 64 provided with a tube 65 also slotted longitudinally and centrally in a plane at right angles to the plane of the slot through the rod 60, for receiving the plates 61. The end of the rod 60 is guided 120 in the socket 66 in the head 64. Pivoted on this head is an arm 67 which constitutes a part of lever pivoted on a stud 68 on the rotating plate 19. The other arm of this lever is provided with a curved rack 69 125 meshing with a pinion 70.

It is to be stated at this point that I have described only one of each pair of these devices. It is to be noted that there is another one having a longer spring arm operated by 130

the other cam groove 54 through the roller 56. The two shafts 73 on which the two pinions 70 are mounted have gear segments 71 fixed thereon of equal diameters meshing 5 with each other and they are also arranged to constitute a part of a lever 72 in each case. There is a pair of these for each set, so to speak, and each lever supports a jaw.

10 It is to be noted that there is an upper pair of jaws 75 and a lower pair of jaws 76. The jaws of each pair are pinned or otherwise fixed to their respective shafts 73 alternately. By that I mean that one jaw 15 arm of a pair is pinned to its shaft 73 and the other jaw arm of the same pair is freely rotatable on its pin, but the gear segments 71 cause the two jaws to move oppositely and equally whenever the shafts 73 are rotated although one of them rotates idly so far as one jaw is concerned. The left hand arm of one pair is fixed to the left hand shaft and the right hand arm of the other pair is fixed to the right hand shaft but the 20 motion is always equal and opposite for each pair of jaws. The cams 53 and 54 therefore act through the spring rods 60-64 to yieldingly close the jaws at certain times and thereafter open them.

30 The upper jaws 75 which are designed to engage the smooth part of the bobbins B are formed with metal operating blades, preferably steel. The lower jaws 76 which have to operate over the larger end of the 35 bobbin, which is provided with circumferential ribs, are made of some softer material that will not injure the bobbins, as for example, vulcanized fiber.

40 The operation of the device is as follows:—

The bobbins, as has been stated, are fed by hand or any desired mechanical means, butt downward, into the revolving circle of hoppers at the top. As the tops of the 45 hoppers form a substantially continuous circle, each bobbin will be received in some one of the hoppers. On account of the shape of the same, it will be brought by gravity down into a position in which its butt end 50 drops down through the outlet opening 24 into the tubular guide 22 below. Now, taking up the course of a single bobbin through the machine, let it be assumed that as the mechanism rotates a bobbin drops down 55 through the opening 24 of one hopper just as the latter passes out from under the top of the arm 11. It is carried along with the tube 23 as the stop 29 at that time moves away from the cam 30 and closes and is held 60 by its spring 26 in closed position. Therefore the bottom of the bobbin rests on this stop as the whole machine rotates throughout nearly a whole revolution until the projecting arm on the stop lever engages the cam 30. That swings the stop 29 outside

the tube 22 as shown in Fig. 8 and allows the bobbin to be dropped. It descends in the tubular guide into contact with the arcuate stop 27 below at the bottom and travels along on that as far as that stop goes. 70 Then it passes over the end of the stop and drops down through the bottom of the tubular guide. It is just at this time that the jaws 75 and 76 are closed by their respective cams. They grip the bobbin at a point near the butt by the jaws 76 engaging the rough part of the bobbin just over the butt and the jaws 75 engaging the larger end of the smooth part of the bobbin. This 75 prevents further descent by the action of gravity alone. The arm 37 now comes into contact with the cam 36 and turns the head 35 into the tube 22. The cam groove 51 at this time operates the roller 34 to push down the head 35 which has swung 80 into the tube 22 through the opening. This continues to descend in accordance with the shape of the cam groove above described and the cup-shaped bottom of the head 35 engages the small end of the 85 bobbin and positively forces it down through the jaws 76 and 75 to remove the filling from the bobbin. This head 35 can take the bobbin only to a point at which the small end is a little above the jaws 75 and 90 at this time, as described above, the cam groove 52 moves the roller 41 down and with it the slide 40. The jaws 43 engage the bobbin just over the butt. This motion of the slide causes the jaws to descend pulling 95 the bobbin down positively with them all the way through the jaws 75 and 76.

These parts are rotating all the time about the shaft 12 and as soon as the bobbin is free from the jaws 76 it will also be free 105 to slide down by gravity out of the jaws 43 which do not positively grip it on account of the stops 47. Thus, the bobbin is discharged from the machine. The tubular guide 22 and the jaws 75 and 76 as well as 110 the other parts, of course, continue their rotation. The cams in the bottom of the cylinder then open the jaws 75 and 76 and, as shown at the right hand of Fig. 5, withdraw them within horizontal passages in 115 the supports 20. The movement of the jaws against the edges of these passages strips the waste from these jaws on which it lies and it passes below and is discharged at a certain point. 120

It will be understood, of course, that when the bobbin under discussion dropped on the stop 27 the tube 22 had already received another bobbin above because the stop 29 had at that time moved inwardly 125 into the tube to hold another bobbin at that point. Thus, during a part of the rotation of the machine there are two bobbins in a tube 22 as indicated at the left of Fig. 2. The position at the right in Fig. 2 indicates 130

the parts just before the second bobbin is introduced into the tube 22 from above.

It will be seen from what has been stated that the device is entirely automatic as shown except as to the feeding of the bobbins into the hopper. The bobbins can be introduced into the hoppers faster than the machine can take care of them at times if desired, but only one can pass out of the 10 hopper at a time because the outlet 24 is just big enough to let the butt end of one bobbin through. The several stops 29 close practically as soon as they have opened to discharge a bobbin so that they are in a 15 position to stop the descent of the next bobbin from above just as soon as the previous bobbin has been dropped down by them. This part of the tube practically constitutes an automatic feed for the part of the tube 20 below which constitutes a holder and guide for the bobbin while it is being stripped.

It will be seen that although I have shown the machine as having six bobbin stripping elements it can be made either larger or 25 smaller on the same principle without departing from the scope of the invention as expressed in the claims and that other modifications can be made therein under the same condition. Therefore, I do not wish to be limited to any particular number of 30 bobbin stripping elements or the exact construction of the parts herein shown and described but what I do claim is:

1. A bobbin stripping machine comprising means for stripping waste from bobbins, 35 and a circular series of hoppers for receiving the bobbins dropped therein loosely and guiding them toward the stripping means.

2. A bobbin stripping machine comprising 40 means for stripping waste from bobbins, and a circular series of hoppers for receiving the bobbins and guiding them toward the stripping means, each hopper being of a flaring shape and also having front and 45 rear walls of arcuate configuration, said series of hoppers together constituting a complete circle.

3. A bobbin stripping machine comprising 50 a series of hoppers for receiving the bobbins and guiding them toward a stripping means, each hopper having front and rear walls of arcuate configuration, and together constituting a complete circle.

4. A hopper for a bobbin stripping machine comprising front and rear parallel 55 arcuate walls and end walls and having sides which slope gradually toward the discharge end, said discharge end having a single opening therein toward which the 60 walls converge and of a size sufficient to receive only the butt end of a bobbin and discharge it therefrom.

5. In a bobbin stripping machine, the 65 combination of means for stripping waste from a bobbin, a hopper for directing the

bobbins to the stripping means, said hopper having front and rear parallel arcuate walls and end walls and having sides which slope gradually toward the discharge end, said discharge end having a single opening therein toward which the walls converge and of a size sufficient to receive the butt end of a bobbin and discharge it therefrom, and a 70 guide in registration and in axial alignment with said discharge opening for receiving 75 the bobbins therefrom.

6. In a bobbin stripping machine, the combination of a plurality of means for stripping waste from bobbins arranged in a circle, a circular series of hoppers for receiving the bobbins and guiding them toward the stripping means, each hopper being of a flaring shape and also having front and rear walls of arcuate configuration, said series of hoppers together constituting a 80 complete circle, and a circular series of guides, one at the end of each hopper, located in position to receive the bobbins therefrom and to direct them to the stripping means. 85

7. In a bobbin stripping machine, the combination of means for stripping waste from bobbins, a circular series of hoppers for receiving the bobbins and guiding them toward the stripping means, each hopper being of a flaring shape and also having front and rear walls of arcuate configuration, said series of hoppers together constituting a 90 complete circle, and a tubular guide at the end of each hopper located in position to receive the bobbins therefrom and to direct them to the stripping means. 95

8. In a bobbin stripping machine, the combination with a hopper for receiving the bobbins, a guide at the end of the hopper, and jaws at the opposite end of the 100 guide for engaging the bobbin to strip the waste therefrom, of means for rotating the hoppers, guide and jaws about a common axis at a distance from them. 110

9. In a bobbin stripping machine, the combination with a vertical shaft, of a series of vertical bobbin stripping devices located 115 parallel thereto and supported therefrom, means for rotating said stripping devices about the shaft, and means for guiding the bobbins downwardly into the stripping devices. 120

10. In a bobbin stripping machine, the combination with a shaft, of a series of bobbin stripping devices located parallel thereto and supported therefrom, means for feeding the bobbins longitudinally in a direction 125 parallel with the shaft, and means for rotating said stripping devices about the shaft. 130

11. In a bobbin stripping machine, the combination of a series of rotary guides for the bobbins located in position for receiving 135

the bobbins, with jaws for stripping the filling from the bobbins arranged to rotate with the guides, and means also rotatable for pushing the bobbins through the guides.

5 12. In a bobbin stripping machine, the combination of a series of rotary bobbin receiving hoppers, and a corresponding series of guides for the bobbins rotatable with the hoppers and located in position for receiving the bobbins therefrom, with jaws for stripping the filling from the bobbins arranged to rotate with the guides, and means also rotatable for pushing the bobbins through the guides.

15 13. In a bobbin stripping machine, the combination with a hopper for receiving the bobbins, a guide at the end of the hopper, means for entering the guide and pushing the bobbin therealong away from the hopper, and jaws at the opposite end of the guide for engaging the bobbin to strip the waste therefrom as the bobbin is pushed through, of means for rotating the hoppers, guide, pushing means and jaws about a common axis at a distance from them.

20 14. In a bobbin stripping machine, the combination with a guide for receiving the bobbin, means for entering the guide and pushing the bobbin therealong, and jaws at the end of the guide for engaging the bobbin to strip the waste therefrom as the bobbin is pushed through, of means for rotating the guide, pushing means and jaws about a common axis at a distance from them.

25 15. In a bobbin stripping machine, the combination with a central stationary vertical shaft, of a series of hoppers arranged therearound in a circle, means for supporting said hoppers from the shaft and rotating them on it, a series of vertical guides under the hoppers in position for receiving bobbins therefrom, means at the bottoms of the guides for stripping the bobbins as they pass down through them, and means for supporting said guides and stripping means to rotate with the hoppers.

30 16. In a bobbin stripping machine, the combination with a vertical central stationary shaft, of a disc mounted at the bottom of said shaft and a spider at the top of said shaft, both rotatable thereon, a series of hoppers for receiving the bobbins supported by said spider and located vertically, a series of tubular guides supported by said disc and located under the hoppers to receive the bobbins therefrom, and a corresponding series of jaws carried by said disc for stripping the waste as the bobbins pass down through, and are discharged from, the bottoms of said guides.

35 17. In a bobbin stripping machine, the combination with a vertical central stationary shaft, of a disc mounted at the bottom of said shaft and a spider at the top of said

with respect to said disc, a driving shaft, gearing for rotating said shaft from the driving shaft, a series of hoppers for receiving the bobbins supported by said spider and located vertically, a series of tubular guides supported by said disc and located under the hoppers to receive the bobbins therefrom, and a corresponding series of jaws carried by said disc for stripping the waste from the bobbins as they pass down through, and are discharged from, the bottoms of said guides.

40 18. In a bobbin stripping machine, the combination with a vertical central stationary shaft, of a disc mounted at the bottom of said shaft and a spider at the top of said shaft, both rotatable thereon, a gear fixed with respect to said disc, a driving shaft, gearing for rotating said shaft from the driving shaft, a series of tubular guides supported by said disc to receive the bobbins, and a corresponding series of jaws carried by said disc for stripping the waste from the bobbins as they pass through, and are discharged from, the bottoms of said guides.

45 19. In a bobbin stripping machine, the combination of a series of vertical guides, means for guiding the bobbins into the guides with one end down, said guides being arranged in a circle, means for rotating said guides about the vertical axis of said circle, a series of stops, one for each guide, each adapted to enter its guide to receive a bobbin thereon and carry it part way around with the guide, and stationary means for withdrawing said stop from its guide to allow the bobbin to drop down from the guide.

50 20. In a bobbin stripping machine, the combination of a series of vertical guides, arranged in a circle and each having a side opening, means for rotating said guides about the vertical axis of said circle, a series of stops, one for each guide, each adapted to enter its guide to receive a bobbin thereon and carry it part way around with the guide, stationary means for withdrawing said stop from its guide to allow the bobbin to drop down from the guide, each of said stops comprising a plate pivoted on a vertical axis, and a spring for normally forcing said plate inwardly through said opening in the side of the guide into central position therein.

55 21. In a bobbin stripping machine, the combination of a series of vertical guides arranged in a circle, means for rotating said series of guides about the vertical axis of said circle, a series of stops, one for each guide, each adapted to enter its guide to receive a bobbin thereon and carry it part way around with the guide, stationary means for withdrawing said stop from its guide to allow the bobbin to drop down from the guide, each of said guides extending be-

5 low said stops and being open at the bottom, and an arcuate stationary stop located under the path of travel of said guides for a distance to hold a bobbin against being discharged from the guides until they pass beyond the arcuate stop.

22. In a bobbin stripping machine, the combination of a series of vertical guides, said guides being arranged in a circle, means 10 for rotating said guides about the vertical axis of said circle, a series of stops, one for each guide, each adapted to enter its guide to receive a bobbin thereon and carry it part way around with the guides, stationary 15 means for withdrawing said stop from its guide to allow the bobbin to drop down from the guide, means movable with each guide for engaging a bobbin as it emerges therefrom at the bottom and resisting its 20 further descent, and means adapted to enter each guide below said stop and movable down in the guide to positively push the bobbin out of the bottom thereof.

23. In a bobbin stripping machine, the combination of a circular series of tubular 25 guides arranged vertically for receiving the bobbins with their butt ends down, an arcuate stop along the bottom of the path of travel of said guides for preventing the bobbins from issuing from the guides while they are passing over said stop, jaws movable with the guides for engaging a bobbin where it projects below the bottom of a guide, and a laterally movable pushing device 30 for engaging the upper end of a bobbin therein and pushing it through the jaws.

24. In a bobbin stripping machine, the combination of a circular series of tubular guides rotatable about the center of the 40 circle, each guide having an opening in its side, a guiding member adjacent the first named guides and rotatable with them, a slide on the guiding member having a head adapted to move laterally into the opening in the guide, means for forcing the slide along the guides as they rotate to push a bobbin positively from the tubular guide, and jaws rotatable with the guides and located at their ends for engaging the 45 bobbins as they emerge from the guides for stripping the waste therefrom.

25. In a bobbin stripping machine, the combination of a series of bodily movable 55 vertical tubular guides, each guide having an opening in its side, a guiding member adjacent the first named guides and movable with them, a slide on the guiding member having a head adapted to move laterally into the opening in each guide, means for 60 forcing the slide down as the guides move to push a bobbin positively from the tubular guide, jaws movable with the guides and located below them for engaging the bobbins as they emerge from the guides for stripping the waste therefrom, and means below the 65

guides movable with them for engaging the butt ends of the bobbins and positively pulling them down through the jaws.

26. In a bobbin stripping machine, the combination of a circular series of guides 70 rotatable about the center of the circle, each guide having an opening in its side, a guiding member adjacent the first named guides rotatable with them, a slide on the guiding member having a head adapted to move laterally into the opening in the guide, means for forcing the slides along the guides as they rotate to push a bobbin positively from the tubular guide, jaws rotatable with 75 the guides and located beyond them for engaging the bobbins as they emerge from the guides and for stripping the waste therefrom, and means beyond the guides rotatable with them for engaging their butt ends and positively pulling them through 80 the jaws, said last named means being located on the guiding means and movable therealong.

27. In a bobbin stripping machine, the combination of a series of movable guides 90 for the bobbins, a corresponding series of guiding frames mounted to move with the guides, a series of pushers, one for each guide, located on said guiding frames and guided thereon, a series of pullers also 95 mounted on said guiding frames and having means beyond their respective guides for engaging the butt ends of the bobbins and pulling them positively out of the guides, jaws mounted adjacent to each guide for 100 engaging the bobbins and stripping waste therefrom as they move out of the guides, and means mounted in stationary position for operating said pushers and pullers automatically as the guides move.

28. In a bobbin stripping machine, the combination of a circular series of guides for the bobbins, a corresponding series of guiding frames mounted to rotate with the guides, a series of pushers, one for each 110 guide, a series of pullers also mounted on said guiding frame and having means beyond their respective guides for engaging the butt ends of the bobbins and pulling them positively out of the guides, jaws mounted adjacent to each guide for engaging the bobbins and stripping waste therefrom as they move out of the guides, a stationary vertical shaft about which the guides, guiding frame and jaws are rotatable, a stationary cylinder on said shaft having cam grooves in its cylindrical surface, and means controlled by said cam grooves for moving the pullers and pushers.

29. In a bobbin stripping machine, the combination of a series of guides for the bobbins, a series of pushers and a series of pullers having means for engaging the bobbins and moving them positively along 120 the guides, jaws mounted adjacent to each 125

guide for engaging the bobbins and stripping waste therefrom as they move out of the guides, a stationary vertical shaft about which the guides and jaws are rotatable, a stationary cylinder on said shaft having cam grooves in its cylindrical surface, means operated by said cam grooves for moving the puller and pusher, said cylinder having cam grooves on its end surface, and means connected with the last named cam grooves for opening and closing the jaws.

30. In a bobbin stripping machine, the combination of a stationary shaft, a cam member on said shaft, a disc rotatable about said shaft, a series of tubular bobbin guides carried by the disc and rotatable with it, a series of pairs of jaws at the end of said guides, and yielding means controlled by said cam member for opening and closing 20 said jaws periodically.

31. In a bobbin stripping machine, the combination of a central stationary shaft, a cam member fixed to said shaft, a disc rotatable on said shaft, a series of tubular 25 bobbin guides carried by the disc and rotatable with it, a series of pairs of jaws, each pair being located at the bottom of one of said tubular guides, yielding means carried by said disc and controlled by said cam 30 member for opening and closing said jaws periodically, said yielding means comprising a pair of concentric rods slidable longitudinally with respect to each other, said rods having diametrical passages there- 35 through, two plates located in said passages, a spring between the plates for forcing the plates away from each other and normally acting to force the rods apart, and a system of levers at the end of each set of rods 40 transmitting motion from the rods to the jaws.

32. In a bobbin stripping machine, the combination with a rotary series of bobbin guides, of a corresponding rotary series of 45 jaws arranged to grip the bobbins as they emerge from the guides to strip the waste therefrom, each pair of jaws being pivoted on individual parallel axes, means connecting the jaws to cause them to rotate in unison 50 toward and from each other, a lever for each pair of jaws having means for rotating said means as the guides rotate, a stationary cam, and means connected with said cam for oscillating said levers as the bobbin guides rotate.

33. In a bobbin stripping machine, the combination with a rotary series of bobbin guides and a stationary cam, of a corresponding rotary series of jaws arranged to grip the bobbins as they emerge from the 60 guides and strip the waste therefrom, each pair of jaws being pivoted on individual parallel axes, gear segments connecting the jaws to cause them to rotate in unison toward and from each other, a lever for each 65 pair of jaws having means for rotating one

of said gear segments, means connected with said cam for oscillating said levers as the bobbin guides rotate, a lever having a roller for engaging the cam, a pair of pins, one connected with each pair of levers and telescopingly arranged, said pins having longitudinal diametrical slots therethrough, two plates passing through said slots, and a spring mounted on the telescoping pin operating at its ends on said plates to force 70 them apart and hold the levers apart yielding. 75

34. In a bobbin stripping machine, the combination of a bobbin guide open at the end, means for pushing a bobbin through 80 the open end of the guide, a pair of jaws, means for yieldingly forcing the jaws together against the bobbin, a slide movable parallel with the axis of the guide, a pair 85 of levers mounted on the slide, each having a jaw at one end, said levers being yieldingly connected at the other end to force the jaws inwardly to engage the bobbin over its butt end at a point beyond the first named jaws, and means for moving 90 the slide outwardly to positively pull a bobbin through the jaws.

35. In a bobbin stripping machine, the combination of a bobbin guide open at the end, means for pushing a bobbin through 95 the open end of the guide, a pair of stripping jaws, means for yieldingly forcing said jaws together against a bobbin, a slide movable parallel with the axis of the guide, a pair of levers mounted on the slide, each having a 100 pulling jaw at one end, said levers being yieldingly connected at the other end to force the pulling jaws inwardly, stops on said slide for holding the jaws thereon in a position in which they do not grip the bobbins 105 but engage over its butt end to enable them to pull it through the jaws, and means for moving the slide to positively pull a bobbin out of the guide and through the jaws.

36. In a bobbin stripping machine, the combination of a bobbin guide, means for advancing a bobbin therethrough and out at its end, a pair of steel jaws located in position to grip a bobbin at a position near the end of the guide, a second pair of jaws having 110 grip surfaces of vulcanized fiber located beyond the first named jaws, and means for yieldingly closing both sets of jaws on a bobbin when it moves through the guide. 115

37. In a bobbin stripping machine, the combination of a bobbin guide, a pair of steel jaws located in position to grip a bobbin near the end of the guide, a second pair of jaws having grip surfaces of vulcanized fiber located beyond the first named 120 jaws, and means for yieldingly closing both sets of jaws on a bobbin. 125

In testimony whereof I have hereunto affixed my signature.

ERNEST H. VOWLES.
